UNITED STATES PATENT OFFICE

160,154

COMBINED BRACELET AND LIPSTICK HOLDER

Albert Flamand, Paris, France

Application April 28, 1949, Serial No. 2,315

Term of patent 3½ years

(Cl. D45—4)

To all whom it may concern:

Be it known that I, Albert Flamand, a citizen of France, residing at Paris, have invented a new, original, and ornamental Design for a Combined Bracelet and Lipstick Holder, of which the following is a specification, reference being had to the accompanying drawing, forming part thereof, and in which

Fig. 1 is a front elevation of a combined bracelet and lipstick holder embodying my design; and

Fig. 2 is a plan view thereof.

I claim:

The ornamental design for a combined bracelet and lipstick holder, as shown and described.

A. FLAMAND.
